UNITED STATES PATENT OFFICE.

WALTER H. SAWYER, OF PHILADELPHIA, PENNSYLVANIA, ASSIGNOR TO HARRY R. KEENE, OF PHILADELPHIA, PENNSYLVANIA.

SALES-CHECK HOLDER AND NOTCHER THEREFOR.

1,399,887.

Specification of Letters Patent. Patented Dec. 13, 1921.

Application filed August 15, 1919. Serial No. 317,801.

To all whom it may concern:

Be it known that I, WALTER H. SAWYER, a citizen of the United States, residing at Philadelphia, in the county of Philadelphia, and State of Pennsylvania, have invented new and useful Improvements in Sales-Check Holders and Notchers Therefor, of which the following is a specification.

10 The invention relates to sales slip and check holders and has for an object to provide a device for holding a supply of sales slips, checks or tickets and for indicating thereon, in the individual distribution there- 15 of, certain amounts or other designations indicative, for instance, of the cost of goods or merchandise purchased.

The invention is particularly adapted for use in restaurants and lunch rooms for the 20 convenient holding of price slips of sales, and for the ready distribution thereof to the patrons, either before or at the time they receive the foods ordered, with means for indicating on the slips the values of the 25 foods ordered or consumed so that the patron and the cashier can immediately determine the total amount of the purchases made. To this end, instead of employing the usual punching device or other expensive or 30 complicated form of mechanism, I provide a simple means for notching the sales slip adjacent to the numbers or values thereon, thus indicating which of said numbers represents the cost to the customer of the food 35 purchased by him.

Although I am aware that various forms of sales slip holders and notching devices therefor, have been used heretofore, I aim to provide, among other features, a holder 40 and notcher of simple design and construction and which can be cheaply manufactured to accomplish the desired result, the holder particularly being adapted to accommodate loose or bound packs of sales slips in such 45 a manner that the removal of the body portions thereof from the usual stubs can be quickly accomplished without tearing the slips.

In the further disclosure of the invention 50 reference is to be had to the accompanying

drawings, constituting a part of this specification, in which similar characters of reference denote corresponding parts in all the views, and in which,—

Figure 1 is a perspective view of the article, looking at the front thereof.

Fig. 2 is a perspective view of the article, looking at the rear thereof.

Fig. 3 is a rear elevation showing a slip in position to be notched.

Fig. 4 is a vertical longitudinal sectional view taken through the article.

Fig. 5 is a similar view with the sales slips and notches removed and the binding and retaining member shown in raised or open position, and

Fig. 6 is a vertical longitudinal sectional view taken through a slightly modified form of my invention, the dotted line indicating the open position of the retaining member.

Referring more particularly to Figs. 1 to 5 inclusive, I provide a back or supporting plate 10, formed with upturned sides 11 which are longitudinally slit as at 12 to 25 form downwardly projecting gripping ears or elements 13, the latter being of a spring-like nature and at the free ends curved inwardly to extend into opposed notches 14 in a pack of sales slips 15, thus supporting 30 the slips in the holder along the lines of severance of the body portions 15^a from the stub portions 15^b. Each ear or element 13 has a medial outwardly flared portion 13^a and mounted to swing over the ears and engage with the flared portions thereof, is a binding retaining member 16, the sides 16^a thereof, by contact with the flared portions, forcing the free ends of the spring-like ears or elements 13 into the notches 14. A cross 35 pin or screw 17 serves to connect the member 16 with the sides 11 of the plate 10, passing through openings 17^a in the sides 11 and openings 17^b in the sides 16^a, a suitable nut 18 being threaded on to the free end of the screw 17. This connection between the plate 10 and member 16 permits of swinging the member on the plate and the latter when 40 swung back provides sufficient space between the ears to permit of the insertion of

45 50 55 60 65 70 75 80 85 90 95 100

the insertion of

the pack of sales slips into the holder, the member when swung into closed position, bearing down upon the stubs of the pack to secure the pack against accidental removal 5 from the holder and at the same time binding the ears against the sides of the stubs of the pack.

It will be readily apparent that with a construction of the character set forth a 10 small or large pack of the sales slips can be arranged in the holder, whether the slips be relatively loose or bound together at their stub ends and that furthermore, the falling out of any or all of the slips from 15 the holder, during the process of tearing off the top slip, is positively prevented. This is primarily due to the provision of the spring ears and the binding of the latter into positive contact with the sides of the 20 stubs, together with the forcing of the free ends of the ears into the notches 14 in line with the line of severance of the main or body parts of the sales slips from the stubs thereof.

25 Although the described holder can be employed by itself for the retention of the sales slips as mentioned and used only for this purpose, I preferably provide an additional part for the notching of the sales slips to 30 indicate particular values thereon and to this end I provide a notcher 19 formed by a backing plate 20, bent at its upper end to form a hook 21 and at its lower end formed to a point to provide the notcher proper. The supporting plate 10 is provided with an aperture 22 and similarly the hook of the notcher has openings 23, 24 therein, the openings 22, 23 and 24 being adapted to register when the notcher is 35 40 plied to the holder by sliding the plate 20 between the supporting plate 10 and the pack of sales slips 15 with the hook end of the notcher overlying the back of the supporting plate. A carrying member 25 now has its hook portion 26 snapped through the registering openings 22, 23 and 24 thus 45 not only providing an effective means for carrying the holder but also retaining the combined backing plate and notcher in positive engagement with the holder and preventing accidental removal of the former 50 relative to the latter.

Attention is particularly called to the relative arrangement of the combined backing 55 plate and notcher and pack of sales slips, and referring to Figs. 2, 3, and 4 it will be seen that the point or notching end of the plate and notcher lies against the lowermost sales slip and does not extend the full length 60 of the latter. With this arrangement the pack of sales slips and in fact the lowermost sales slip acts as a backing for the particular sales slip that is to be notched, as illustrated in Fig. 3. I have found that this construction and arrangement provides for the

manufacture of a cheaper holder and notcher and by reason of the flexible and cushioning pad-like backing, such as the pack of sales slips affords, the accurate notching of a particular sales slip is more easily and effectively accomplished. I have also found that the positioning of the particular sales slip between the pack and the notcher and in direct contact with the lowermost sales slip, utilizes a backing that will readily give to the pressure of the fingers of the operator and enable him to closely bind the backing and notcher against the particular sales slip to the end that the material of the backing, being of the same nature as the slip operated upon, will hold the latter from slipping while the notching thereof is effected.

In Fig. 6, I disclose a slightly modified form of my invention, as to the holder, the sides 11 of the supporting plate in this instance, having elongated openings or slots 17^c with which openings 17^b of the member 16, register, so that the cross pin or screw 17 will pass through the openings 17^b and the slots 17^c. With this form of construction the member 16 is not only disposed for swinging engagement with the supporting plate 10, as in the preferred form of my invention, but it is also adapted to slide relative to the sides 11 of the plate, thus facilitating the operating of the device as to the insertion of a pack of sales slips, the modified form being particularly adapted to the accommodation of sales slips of unusually large size and whose stubs are considerably 100 larger than the stubs of the average sales slips.

I am aware that various forms of sales check holders and notching devices for sales checks have been used heretofore. I aim, 105 with my device however, to produce a holder which can be cheaply manufactured; in which the parts, because of their simplicity of construction and operation, cannot readily get out of order; which can be 110 adapted to various different forms of sales slips and is particularly adaptable to what are known as indented or notched tickets or sales slips; in which the relation of the holder to the sales slips, insures a positive removal of the body of the sales slip from the stub thereof, along the pre-arranged line of severance without danger of unduly tearing the sales slips or stubs along any other line; in which the holder can be readily employed to secure sales slips in loose or bound packs or in which one or more packs can be accommodated in the holder at one time; in which the holder can be employed independently of the marker or notcher; in 115 which the provision of my particular form of notcher or notching plate or member is a decided saving of metal by having the sales slips act as the backing when a particular removed sales slip is operated upon 120 125 130

by the notcher and in which the material of the sales slip to be notched being the same as the material of the still unused sales slips, will, upon arranging the particular sales slip in position to be notched, insure the latter being held from slipping during the notching operation. Finally the relation of the member 16 to the spring-like ears 13 insure a secure grip of the ears upon the sales slips or packs of sales slips in the side notches thereof, thereby securely holding the sales slips or packs against accidental re-

moval whether the sales slips be relatively loose or bound together.

Having described my invention, I claim— 15

A holder for paper sales checks comprising means to surround and hold a pack of checks at one end of the pack, and a backing plate having at one end a hook straddling and detachably held on one wall of the holding means. 20

In testimony whereof I affix my signature.

WALTER H. SAWYER.
